UNITED STATES PATENT OFFICE.

EUGENE BEGGS, OF PATERSON, NEW JERSEY.

BOILER.

SPECIFICATION forming part of Letters Patent No. 415,894, dated November 26, 1889.

Application filed February 13, 1889. Serial No. 299,778. (No model.)

To all whom it may concern:

Be it known that I, EUGENE BEGGS, a citizen of the United States, residing at Paterson, Passaic county, State of New Jersey, have invented a new and useful Improvement in Boilers, of which the following is a specification, reference being had to the accompanying drawings, forming a part thereof.

My invention relates to water-tube boilers, and has for its object a water-tube boiler wherein is secured cheapness of construction, economy of fuel, and a boiler which is easily taken apart for repairs, cleaning, removal, &c.

The objects sought I attain by the construction shown in the accompanying drawings, which will be hereinafter fully described and claimed, in which—

Figure 1 is a side elevation of the boiler, the reservoir being removed in such figure. Fig. 2 is a transverse sectional elevation on line *w w* of Fig. 1. Fig. 3 is a longitudinal sectional elevation of the same on line *x x* of Fig. 4. Fig. 4 is a front elevation of the boiler. Fig. 5 is a rear elevation of the same. Fig. 6 is a plan on line *y y* of Fig. 3. Fig. 7 is a detail of headers, water-box tubes, &c., part sectional, on line *z z* of Fig. 6. Fig. 8 shows in elevation the position of the tubes in the water-box, and Fig. 9 is a section showing how the water-chambers, &c., are connected.

A represents a water-tube boiler of new construction, in the fire-box *B* of which is arranged a series of grates *B'*. The grates *B'*, the edges of which are rounded off, are adapted to act in concert with rotary bars *B²*, which latter are arranged with reference to the grates between and on each side of the same, which, while turning upon their axis when the grates are being operated, accommodate themselves to the movement of the grates, which action of the bars tends to crush obstructing particles and prevent clogging. The grates *B'*, which are arranged in common with rotary bars *B²* in the ash-box *A'*, are provided with arms *C*, that connect with a link *C'* by means of a pivot-bolt *a*, while one of the said arms also connects with a lever *C³* by means of a link *C²*, which lever is fixed to the ash-box *A'* by pivot *2* and lug *3*, and which affords an easy and convenient means to operate the grates. The grate, however, does not form a part of the present in-

vention, and many other approved forms of grate may be used in place of the one described.

On each side of the fire-box *B* above the grates *B'*, where combustion takes place, is arranged water-chambers *D*, that connect with transversely-arranged water-chambers *D²* by means of a connecting-joint *D'*. These water-chambers *D* and *D²* are arranged around the fire-box with reference to each other, and, being connected, form a water-space on all sides of the fire-box for the circulating of water to be heated, as hereinafter stated. The chambers *D* are provided with lugs *D³*, which latter pass through the chambers and project into the fire-box, this construction of the chambers *D*, while it furnishes increased heating-surface for the chambers, also gives additional strength to the same.

At the ends of the frame there are arranged headers *F F'*, which headers have formed in the outer ends of the same, outside of the boiler-frame, recesses *E'* to accommodate bolts *E*, by which the boiler-frame is fastened together, and by which the frame is firmly held in position, the bolts not being subjected to heat to cause expansion and contraction of the same. In addition to the recessed ends *E'* to accommodate bolt *E*, by which the boiler-frame is held in position, the headers *F F'* are provided with water-spaces *F³* and a connection *F⁴*, by which the headers are adapted to connect with water-boxes *G*, that are arranged in the fire-box *B* with reference to the headers and their connection therewith by means of a connection *F⁴*, as shown. The water-boxes *G*, which are provided with lugs *F²*, that jam against the headers to hold the boxes *G* in position, are also provided with two sets of tubes *H*, which tubes are arranged in the water-boxes, as shown in Figs. 2 and 8 of the drawings, there being considerable space left between each one of the upper set of tubes in order that the lower set of the same may be conveniently cleaned, repaired, removed, &c.

The headers *F F'* connect with a reservoir *L* by means of pipes *K K'*, and also connect with chambers *D* by means of pipes *N N'*, as shown. The water passes from the reservoir *L* through the pipe *K* into header *F*, and from thence the water passes through the pipe *N* into chambers *D* and *D²* and through

the tubes H into box G'. The water having been heated while passing through the chambers and tubes around and over the fire-box, as stated, the heated water and steam pass 5 from the chambers D through pipe N' and from box G' into header F', and from header F' through the pipe K' into the reservoir L, to be returned through the reservoir, pipes, headers, tubes, and chambers, &c., as indicated by arrows, to be reheated. A continuous circulation of water to be heated and reheated is thus maintained without loss of heat from the fire-box, with a proportionate saving of fuel.

15 The connections D' and F' between the chambers D D², headers F, and boxes G, which are composed of the usual brass bush, as shown in Figs. 7 and 8, may be formed with a union or other connecting means without changing 20 the nature of my invention; hence I do not confine myself to the precise construction of the connections shown.

The boiler-frame is composed of a cast-metal fire-box B, that rests on lugs A², formed therefor in the ash-box A', while the remaining portion of the boiler-frame is formed of a wrought-iron plate or plates o, which latter are fastened to the fire-box B by set-screws P, the entire structure being held in position by 25 bolts E and n and set-screws P, as shown, and may be taken apart for repairs, cleaning, removal, &c., in a few minutes. The top of the frame is provided with asbestos covering R, which is arranged in angle-irons S, supported 30 by standards J', while a bottom plate R' is arranged in and supported by like angle-irons S', Fig. 3. There is also supported by standards J' a smoke-box J, which box is provided with a door J², which latter affords an easy 35 way of controlling the draft.

Having described my invention, I claim as new and desire to secure by Letters Patent—

1. In a boiler, the combination, with the fire-box, of the longitudinal water-heating chambers D in the outer wall of the fire-box, provided with a series of strengthening-lugs D³, extending across the inside of said chambers and projecting into the fire-box, the transverse water-heating chambers D² in the end walls of the fire-box, and the water-tight connecting-joints D' between the said chambers and permitting the water to circulate all around the fire-box, substantially as set forth. 45

2. In a boiler, the combination, with the headers F and F', provided with connections F⁴, for communicating with the water-boxes, of the bolts E at each end of the headers for holding them in position, the water-boxes G, secured to said connections, and the tubes H, uniting the water-boxes, substantially as and 50 for the purpose set forth. 55

3. The water-boxes G, having lugs F² and two sets of tubes H, the boxes arranged with reference to headers F F' in the fire-box and connected with said headers, by which water 55 is circulated through the headers, boxes, and tubes to be heated, substantially as described.

4. The boiler-frame composed of a cast-metal fire-box A' and B and plate or plates o, the frame held in position by bolts E n and 70 set-screws P, substantially as described and shown.

5. The combination, with the headers F F' and chambers D, of the reservoir L, pipes K K', and pipes N N', all arranged to operate 75 substantially as described and shown.

6. The combination, with the boiler-frame, of the covering R, plate R', box J, door J², and supports J', as described and shown.

EUGENE BEGGS.
